UNITED STATES PATENT OFFICE

144,071

DESIGN FOR A FISH LURE BODY

Kenneth D. Richards, Gardner, Mass.

Application September 10, 1945, Serial No. 122,000

Term of patent 7 years

(Cl. D31—4)

To all whom it may concern:

Be it known that Kenneth D. Richards, a citizen of the United States, residing at Gardner, in the county of Worcester and State of Massachusetts, have invented a new, original, and ornamental Design for Fish Lure Body, of which the following is a specification, reference being had to the accompanying drawing, forming part thereof.

Fig. 1 is a top plan view; and
Fig. 2 is a view in side elevation of a fish lure body showing my new design.

I claim:

The ornamental design for a fish lure body, as shown.

KENNETH D. RICHARDS.
